CHARLES G. JOHNSON, OF BRIDGEPORT, CONNECTICUT, ASSIGNOR TO WARNER BROTHERS COMPANY, OF BRIDGEPORT, CONNECTICUT, A CORPORATION OF CONNECTICUT.

BUCKLE.

1,140,040.

Specification of Letters Patent.

Patented May 18, 1915.

Application filed June 3, 1914. Serial No. 842,549.

To all whom it may concern:

Be it known that I, CHARLES G. JOHNSON, a citizen of the United States of America, and a resident of Bridgeport, county of 5 Fairfield, State of Connecticut, have invented a new and useful Improvement in Buckles, of which the following is a specification.

This invention relates to buckles and more 10 specifically to those types of buckles comprising a clamping member movable relatively to the frame of the buckle, and co-operating with an auxiliary element, such as a portion of the frame of the buckle, to 15 form a clamp, the webbing or strap of leather, fabric or the like, being interposed between such auxiliary element and the clamping member, the movement of the clamping member being controlled by a 20 suitable lever.

In explanation of my invention, I have referred hereinafter to certain preferred forms of my buckle having a frame formed 25 of a transverse bar serving as a clamping bar, longitudinal bars connected to said clamping bar, and another transverse bar serving as the pivot bar. The longitudinal bars may be substantially parallel to each other, and lying practically in a plane excepting at their respective portions adjacent the clamping bar. The clamping member is in the form of a sliding clamp movable in a plane parallel to the plane of the frame said sliding clamp having a clamping 30 portion disposed at an angle to the body of the sliding clamp, said angle being of proper magnitude relative to the clamping bar whereby the pressure effected by the sliding clamp on the webbing or strap will 35 withstand the greatest strains, such as would be met with in the use of the buckle as a baggage buckle. The sliding clamp is preferably controlled by a cam secured to the lever, said sliding clamp being guided in 40 its movement by lugs attached respectively on the upper sides of the longitudinal members, and further by one or more transverse bars attached on the lower sides of the longitudinal bars. Such lower transverse bar, or 45 one of such lower transverse bars, if two or more are employed, is disposed relatively to the sliding clamp when in closed position

whereby the strains exerted by the webbing or strap are transmitted to and borne by such lower transverse bar, and thereby also 55 relieving the cam of substantially all strains when the parts are in closed position. In such types of buckle, I have found it desirable to positively connect the sliding clamp with the cam to thereby positively 60 withdraw the sliding clamp away from the clamping bar when the lever is moved to open position.

Other features and objects of my invention will be more fully understood from 65 the following description and the accompanying drawings, in which—

Figure 1 is a top plan view of a buckle, comprising my invention, the parts of the buckle being shown in closed position; Fig. 70 2 is a bottom plan view of the same; Fig. 3 illustrates the same buckle when strung with webbing or a strap of leather, fabric or the like; the view is in central longitudinal section and shows the parts of the buckle in 75 closed position; and Fig. 4 is a detail sectional view on line 4—4 of Fig. 2.

Referring to the drawings, the frame comprises the transverse bar 1 serving as a clamping bar, and the substantially parallel 80 longitudinal bars 3, 4, respectively connected to bar 1. The transverse bar 2 comprises stud-like ends serving as pivots and a reinforcing portion of less cross-section interconnecting the stud-like portions. The loop 85 for attaching the fixed end of the webbing or strap comprises the transverse bar 5 connected to extensions of longitudinal bars 3, 4, the fixed end 6 of the webbing being secured about bar 5 by means of rivets 7 or 90 the like. As illustrated, the longitudinal bars 3, 4, the pivot bar 2 and the loop bar 5 are in substantially the same plane, and the clamping bar 1 is disposed somewhat above said plane (see Fig. 3) the respective adjacent portions of bars 3, 4, being suitably curved or bent at an angle.

The sliding clamp 8 comprises a body portion 10, the major part of which is substantially flat and a clamping portion 11 100 disposed at an angle to said body portion 10 and bent upwardly with respect to the clamping bar 1. Such relation of the clamping portion 11 facilitates the insertion of the

running end 12 of the webbing or strap, and at the same time enables the clamping portion 11 to effectively "bite" the webbing or strap at the desired adjusted position, whereby the maximum strains tending to dislodge the webbing or strap 12 from the desired adjusted position are effectually overcome without substantial injury to the material of the webbing or strap.

10 The sliding clamp 8 is guided at the top by the opposite guiding lugs 13, 14, held respectively by longitudinal bars 3, 4. Below the sliding clamp 8 is disposed the lower transverse bar 15 extending from longitudinal bar 3 to longitudinal bar 4, and in a certain position relative to the clamping portion 11 of sliding clamp 8 when the same is in closed position, as will be more fully explained hereinafter. In the drawings, 20 there is also shown the transverse bar 16 disposed below the sliding clamp 8 and extending from longitudinal bar 3 to longitudinal bar 4. Thus, when the sliding clamp is moved longitudinally of the bars 3, 4, the same is guided by lugs 13, 14, and 25 transverse bar 16, said movement in the case illustrated being substantially parallel to the plane of the frame.

30 The operating mechanism of the sliding clamp comprises the lever 18, preferably having oppositely disposed ears 19, 19, integral with the body of lever member 18, said ears 19 respectively embracing the stud-like portions 2, 2 of the pivoting bar. 35 The sliding clamp operating means further comprises the cam portion 20 preferably formed by bending an extension integral with the body of lever member 18, said cam portion comprising the cam surface portion 40 21 and the locking portion 22, said locking portion 22 being shown as extending into contact with the body of lever member 18. The sliding clamp 8 is provided with the angular operating surface 23 coöperating 45 with the cam surface 21 to give an easy movement and coöperating with locking surface 22 to firmly lock the sliding clamp when the lever 18 is in closed position. The loop 24 formed of coacting loop elements is 50 shown extending from sliding clamp 8 rearwardly and adapted to engage the inner face of cam portion 20 when the lever member 18 is moved from closed to open position, thereby facilitating the withdrawal 55 of sliding clamp 8 away from clamping bar 1 when the buckle is opened. The lever member is indicated as having the front portion 25 adapted to project toward or engage the portion 10 of sliding clamp 8 when 60 the lever member 18 is in closed position. It will be noted that the free end of running portion 12 of the webbing or strap will lie snug against the depressed portion 25 of lever member 18 thereby reducing the 65 combined dimensions of the buckle and

strap or webbing when the buckle is in closed position. The lever member 18 is shown provided with opposite finger pieces 26, 26, preferably conforming to the periphery of longitudinal members 3, 4, to thereby 70 reduce the extent of projecting parts when the buckle is in closed position.

It is advantageous to dispose the upper guide lugs 13, 14, more closely toward the pivot of the lever member 18 thereby giving the front or clamping portion 11 of the sliding clamp limited free play vertically in the direction of tensioning or tightening the webbing or strap. Such arrangement improves the facility of inserting the free end of the running portion 12, and also allows the running portion to be pulled through the buckle in the direction to tighten the webbing or strap around the trunk, package or other object while the 85 lever and sliding clamp are in closed position. This improved characteristic of my buckle may be illustrated with respect to Fig. 3 of the drawings, by assuming the webbing or strap to encircle the trunk, package or like object and the running portion 12 to have been inserted between the clamping bar 1 and the sliding clamp 8. The buckle may be then closed as by means of the lever and its cam portion, and the 90 running portion 12 pulled through the buckle in the direction indicated by arrow 17 while the parts of the buckle are in closed position, the running portion 12, however, being pulled vertically upward 100 rather than horizontally, as indicated in Fig. 3. Thus, without manipulating the lever member, the webbing or strap may be pulled to exert the desired maximum pressure on the trunk, package or like object 105 without requiring the closure of the buckle after such desired position has been attained, as is necessary in prior buckles. Upon attaining such desired position, the 110 strap or webbing will be held against the strains tending to dislodge the same by the clamping portion 11 coöperating with the clamping bar 1. It will be noted that the transverse bar 15 frictionally engages the 115 sliding clamp 8 at or adjacent to the clamping portion 11 thereof, and such strains tending to dislodge the webbing or strap will be borne by the said transverse bar 15. It is desirable to provide the sliding clamp 8 with the rib or corrugation 9 extending 120 lengthwise of the sliding clamp 8 and transverse to the angular clamping portion 11, thereby giving increased rigidity. Such rib or corrugation 9 may be disposed in the 125 center of sliding clamp 8 or any number of such ribs or corrugations may be provided for.

Whereas I have described my invention by reference to the specific forms thereof, it will be understood that many changes and 130

modifications may be made without departing from the scope of my invention as defined by the appended claims.

What I claim and desire to secure by Letters Patent is:—

1. In a buckle for webbing or the like, the combination with a frame, of a clamping member comprising a body portion and a clamping portion extending upward at an angle to the plane of said body portion, means for slidably mounting said clamping member on said frame, a stop for opposing movement of said clamping portion in a direction opposite to the direction of said angle when said clamping member is in closed position, said clamping portion being free to yield to movement in the direction of said angle, and a lever comprising a cam portion for controlling said sliding member. 10
2. In a buckle for webbing or the like, the combination with a frame, of a clamping member comprising a body portion and a clamping portion in fixed relation to said body portion extending upward at an angle to the plane of said body portion, means for slidably mounting said clamping member on said frame, a stop in the path of said clamping portion for opposing movement thereof in a direction opposite to the direction of said angle when said clamping member is in closed position, said clamping portion being free to yield to limited movement in the direction of said angle, and a lever comprising a cam portion for controlling said sliding member. 20
3. In a buckle for webbing or the like, the combination with a frame comprising longitudinal bars and a transverse bar, a clamping member co-operating with said transverse bar to form clamping means, means for slidably mounting said clamping member on said longitudinal bars, a bar connected to said longitudinal bars serving to resist movement of the clamping member in a certain direction when the clamping member is in closed position, a lever member comprising a cam portion controlling the sliding movement of said clamping member and means for pivotally mounting said lever member on said longitudinal bars, said movement resisting bar and said pivotally mounting means being disposed on opposite sides of said slidable mounting means. 30
4. In a buckle for webbing or the like, the combination of a frame of the buckle comprising longitudinal bars and a relatively displaced transverse bar, a clamping member comprising a body portion and a clamping portion extending from said body portion in the direction of said displaced transverse bar, said clamping portion forming with said transverse bar a clamp, means for slidably mounting said clamping member on said longitudinal bars, a bar carried by said longitudinal bars and disposed relatively thereto in the direction opposite to the direction of displacement of said displaced bar and adapted to be engaged by said clamping member when said clamping member is in closed position and a lever member comprising a cam portion for controlling the sliding movement of said clamping member. 40
5. In a buckle for webbing or the like, the combination of a frame comprising longitudinal bars and a transverse relatively displaced bar, a clamping member comprising a body portion and a clamping portion integrally connected to said body portion and extending angularly therefrom in the direction toward said transverse displaced bar, means fixed to said longitudinal bars for slidably mounting said clamping member thereon, a bar fixed to said longitudinal bars and positioned adjacent said transverse displaced bar and adapted to be engaged by said clamping portion when the same is in closed position, a lever member comprising a cam portion for controlling the sliding movement of said clamping member and means for pivotally mounting said lever member on said longitudinal bars. 50
6. In a buckle for webbing or the like, the combination of a frame comprising longitudinal bars and a relatively displaced transverse bar, a clamping member comprising a body portion and a clamping portion integrally connected to said body portion and extending angularly therefrom in the direction toward said transverse bar, means for slidably mounting said clamping member on said longitudinal bars, a bar serving as a stop for opposing movement of said clamping portion in a direction opposite to the angle of displacement of said transverse bar when said clamping member is in closed position and a lever member comprising a cam portion for controlling the sliding movement of said clamping member. 60

In testimony whereof I have signed this specification in the presence of two subscribing witnesses.
